UNITED STATES PATENT OFFICE.

EUGENE E. STUVER AND CALEB R. ROBBINS, OF BLUE MOUND, ILLINOIS.

LOCK.

1,173,892.

Specification of Letters Patent. Patented Feb. 29, 1916.

Application filed June 7, 1915. Serial No. 32,708.

To all whom it may concern:

Be it known that we, EUGENE E. STUVER and CALEB R. ROBBINS, citizens of the United States, residing at Blue Mound, in 5 the county of Macon and State of Illinois, have invented new and useful Improvements in Locks, of which the following is a specification.

The present invention relates to improvements in locks for sliding doors, and the 10 object of the invention is to simplify and improve the existing art by providing a lock of this class which will automatically lock a door when slid to its closed position, 15 but also whereby the sliding bolt may be thrown into inactive position so that the door may be moved to its closed position without being locked in such closed position.

With the above and other objects in view, 20 the improvement resides in the construction, combination and arrangement of parts set forth in the following specification and falling within the scope of the appended claims.

In the drawings: Figure 1 is an elevation 25 of a sliding door and a casing therefor provided with our improvement, Fig. 2 is a sectional view approximately on the line 2—2 of Fig. 1, Fig. 3 is a transverse sectional view approximately on the line 3—3 30 of Fig. 1, Fig. 4 is a longitudinal sectional view approximately on the line 4—4 of Fig. 1, Fig. 5 is a vertical longitudinal sectional view, the latching bolt being illustrated by the dotted lines in the inoperative position, 35 and Fig. 6 is a perspective view of the casing.

In the drawings, the numeral 1 designates 40 the sliding door and 2 the trim of the casing against which the door abuts when in its closed position.

In the present instance we have illustrated the door provided with a hook bolt and the trim provided with a casing, but it is to be understood that the casing may be 45 applied to the door and the bolt connected with the trim if desired. The hook bolt is indicated by the numeral 3 and has one of its ends pivoted, as at 4, to the door 1. The door is provided with a vertically arranged 50 and with a horizontally arranged stop, the said stops being indicated by the numerals 5 and 6 respectively, and each of said stops may be in the nature of clips each being adapted to engage with the hook bolt when 55 the same is swung to its vertical or inoperative position or to its horizontal or oper-

ative position. The end of the bolt 3 opposite its pivot 4 is formed upon its lower edge with a depending lug providing the hook proper, the same being indicated by the 60 numeral 7, and the said outer edge of the bolt, preferably, is beveled from its center to its opposite longitudinal edges. The bolt at a suitable distance from its hook and upon its upper edge is provided with a 65 notch 8.

The casing which is secured to the trim 70 2 is indicated by the numeral 9, and preferably comprises a substantially U-shaped member including a flat outer face 10, inwardly turned right angular sides 11 which have their ends provided with flat outturned flanges 12, and these flanges 12 are provided with suitable openings for the reception of screws or similar securing devices 13. The 75 sides 11 of the casing 9, at the juncture of the flanges 12 therewith, are formed with elongated substantially rectangular openings 14, the said openings alining and the hook bolt 3, when swung to its horizontal 80 position, is adapted to pass through the opening 14 nearest the said bolt. When the door is slid to its closed position, its beveled edge contacting with the lower wall of the opening, elevates the hooked end of the 85 same, permitting the said end of the bolt to pass through the said second opening 14 and the hook thereof to fall by gravity against the outer side 11 of the casing to 90 lock the door in its closed position.

The pivot 4 is arranged upon the door a suitable distance away from the casing 9, and by swinging the hook bolt 3 upon its pivot to bring the hooked end thereof out of contact with the side of the casing, the door 95 may be readily swung to an open position, as will be readily understood. The horizontal clip 6 while provided with a finger 15 to contact with the outer side of the bolt to sustain the same in proper position to 100 permit of the bolt passing through the openings 14 of the casing, does not engage with the said hook with sufficient friction to prevent the same dropping by gravity as above set forth, but the finger 16 upon the vertical 105 clip 5 is in the nature of a spring and is adapted to frictionally engage with the hook bolt to normally hold the same in its inoperative position.

The sides 11 of the casing are connected, 110 at suitable points, by strips or partitions 17—18', the lower partition being provided

with a square opening 18 and the upper partition 17 being provided with a round opening 19 which is arranged in a line to the square opening 18.

5 The numeral 20 indicates a locking bolt having one of its ends 21 square, the said square end being arranged in the square opening 18 of the partition 17 and the opposite end is round, as at 22, the said round end 10 being received within the round opening 19 of the partition 17'. The bolt 20 is preferably provided with a head 23 which limits the downward movement of the bolt, and the said bolt is provided upon one of its sides 15 with a lateral finger 24 which is arranged within the path of an offset turning arm 25 that is arranged upon the spindle 26 of the operating knob 27, the said spindle passing through suitable openings in the base 10 of 20 the casing 9 as well as through suitable openings in the trim and the casing of the trim and both of the ends of the spindle may be provided with knobs. Surrounding the rounded portion of the bolt 20 beyond its 25 finger 27 and exerting a tension between the said finger and the said upper partition 17' is a helical spring 28 which serves to normally force the bolt downward of the casing to bring the lower end of the same to engage 30 in the notch 8 of the hook member or bolt 3 to lock the door in its closed position. The oppositely beveled or spear shaped end of the pivoted hook bolt 23 permits of the same contact with the lower end of the locking 35 bolt without interfering with the said bolt passing through the elongated opening 15 in the sides of the casing 9, and, of course, upon operating the knobs to return the spindle, the arm 25 will contact with the 40 finger of the locking bolt, elevating the bolt to bring the same out of engagement with the notch 8 of the hook bolt, and when the said hook bolt is swung to bring its hook 7 within the area of the openings 14, the door 45 may be slid to its open position as previously described.

From the above description, taken in connection with the accompanying drawings, the simplicity of the device, as well as the 50 advantages thereof will, it is thought, be

perfectly apparent to those skilled in the art to which such invention appertains without further detailed description.

Having thus described the invention, what we claim is:

1. In combination with a sliding door and a jamb against which the door abuts, of a hook bolt pivoted at one of its ends to the door, vertical horizontal clips for sustaining the hook bolt either vertically or horizontally of the door, a casing having an opening to receive the hooked end of the bolt to permit of the said bolt dropping by gravity to engage with one of the sides of the casing, said hook bolt having a notch, a spring pressed member in the casing adapted to engage in the notch, and means for operating the member to bring the same out of said notch. 55

2. In combination, a stationary member and a slideable member adapted to abut with the stationary member, of a bar having one of its ends pivotally secured to one of the members, the other end of the bar being substantially V-shaped and provided upon 70 its lower edge with a shoulder forming a hook, means upon the door for sustaining the hook member in a vertical or in a horizontal position, a casing upon the second member having openings through which the 75 hooked end of the bar is adapted to pass, said hook adapted to swing by gravity to engage with the casing to one side of one of the said openings, said bar adjacent its hooked end having one of its edges provided 80 with a notch, a spring pressed locking member within the casing and adapted to engage with the notch of the bar, a finger upon the bolt, a knob tumbler, an arm upon the knob tumbler adapted to co-act with the finger 85 to elevate the lock bolt when the knob tumbler is turned in one direction. 90

In testimony whereof we affix our signatures in presence of two witnesses.

EUGENE E. STUVER.
CALEB R. ROBBINS.
